US00D907534S

(12) **United States Design Patent** (10) Patent No.: **US D907,534 S**
 Ying (45) Date of Patent: ** Jan. 12, 2021

(54) **MOTORCYCLE**

(71) Applicant: **Zhejiang Apollo Motorcycle Manufacturing Co., Ltd.**, Zhejiang (CN)

(72) Inventor: **Er Ying**, Zhejiang (CN)

(**) Term: **15 Years**

(21) Appl. No.: **29/694,430**

(22) Filed: **Jun. 11, 2019**

(51) LOC (13) Cl. **12-11**

(52) U.S. Cl.

USPC **D12/110**

(58) **Field of Classification Search**
